CONTROL PANEL FOR A DATA ACCESS ACOUSTICAL COUPLER

John P. Kennedy, Columbus, Ohio, assignor to Mi², Inc.

Filed June 7, 1972, Ser. No. 260,713

Term of patent 14 years

Int. Cl. D14—03

U.S. Cl. D26—14 A

FIG. 3

FIG. 1

FIG. 2

FIG. 4

FIG. 1 is a top plan view of a control panel for a data access acoustical coupler showing my new design;

FIG. 2 is a side elevation thereof;

FIG. 3 is an elevation as seen from the side opposite FIG. 2; and

FIG. 4 is a perspective view thereof, the broken lines are shown for illustrative purposes only.

I claim:

The ornamental design for a control panel for a data access acoustical coupler, as shown and described.
